UNITED STATES PATENT OFFICE.

FRED VOLARE, OF SCOTCH PLAINS, NEW JERSEY, ASSIGNOR TO THE AEOLIAN COMPANY, A CORPORATION OF CONNECTICUT.

PITMAN FOR PNEUMATIC MOTORS.

Original application filed October 26, 1923, Serial No. 670,887. Divided and this application filed June 11, 1926. Serial No. 115,259.

My present invention relates to improvements in pitmen for pneumatic motors, including motors for automatic musical instruments such as pianos and organs, this 5 being a division of my United States Patent No. 1,613,146, issued Jan. 4, 1927, entitled Improvements in pneumatic motors.

The object and nature of my invention is a pitman which is entirely effective for its 10 purpose and at the same time is simple to manufacture and assemble with the parts of the motor which it operatively connects.

The drawings show a pneumatic motor embodying my improvements in their preferred form. In said drawings, Fig. 1 is a face view of said motor; Fig. 2 is a combined vertical section and end view on the line 2—2 in Fig. 1 looking in the direction of the arrows; Fig. 3 is a longitudinal sectional view on a larger scale of one of the pitmen detached, said section being taken on the line 3—3 in Fig. 4 looking in the direction of the arrows; and Fig. 4 is a plan view of the same pitman looking down upon it 25 in Fig. 3.

Before describing my improvements, it will be merely necessary to say by way of preface as to the pneumatic motor proper to which my improvements are applied, that it 30 may be of any usual or preferred construction, the specific type shown in the drawings being merely one of the numerous kinds of pneumatic motors to which my improvements are applicable. For this reason, no 35 detailed description of the pneumatic motor proper is necessary, it being sufficient to point out that 1 designates the motor pneumatics; 2 their slide valves; 3 the crank shaft provided with the sprocket wheel 4 for delivering the power developed by the 40 motor to the drive mechanism; and 5—5 are brackets for supporting the motor in the vertical position shown inside the automatic musical instrument in operative relation 45 with the music-roll and take-up spool mechanism thereof.

The means for operatively supporting the slide valves 2 consists of metal staples 6 driven into the back of the motor with their 50 legs at the sides of the valves and with the upper portion of said staples bent so as to overlie the exposed face of the valves.

Each valve has a metal piece secured thereto consisting of a round cross-sectional

part 7 extending transversely adjacent the 55 exposed face of the valve and supported in that position by the legs 7^a which are preferably flattened so as to be rigidly securable by the screws 8 to the side edges of the valve between the legs of the previously described 60 guide staples 6.

There are six pitmen within my invention shown in Fig. 1, of which three are longer than the others but are otherwise the same in construction. The three long pitmen 9 65 are shown operatively connecting the motor crank shaft with the several valves 2, whereas the short pitmen 9^a connect said crank shaft with the several pneumatics 1. Since, apart from length, there is no difference between the pitmen 9 and 9^a, the following description and reference numerals apply equally to both. Each pitman consists of a strip of springy or resilient metal, 70 preferably spring steel, provided with bent-up, substantially U-shaped ends 9^b. The latter are of such size and shape that they can be sprung over the crank shaft 3 and over the above described round cross-sectioned 75 part 7 of the valves, as shown at 9 and 9^b in Figs. 1 and 2, the resilience of the sides of said U-shaped ends serving to operatively 80 retain the pitmen in position.

To make a better, noiseless bearing, each 85 U-shaped end is lined with a sound-deadening material such as felt, in the form preferably of a strip 10 of such material secured by its ends under the clamping lugs 9^c and 9^d which latter are located adjacent the mouth of each U-shaped end and are preferably formed integral with the pitman. Thus, the lugs 9^c consist of the extremities 90 of the pitman beyond the U-shaped ends bent back so as to grip the material 10, as best shown in Fig. 3, between the said lugs 9^c and the outside of the U-shaped ends 9^b. On the other hand, the lugs 9^d are stamped up from the body portion of the pitman adjacent the U-shaped ends so as to receive 95 under them the material 10 and to clamp 100 same against said body portion of the pitman.

From the foregoing, it will be evident how easily the pitmen can be assembled to connect the crank shaft with the valves by 105 merely snapping the resilient U-shaped ends of the pitmen over said crank shaft and the part 7 of the respective valves. Similarly,

they can be disassembled by prying or forcing their U-shaped ends off the parts with which they are engaged.

The pitmen 9^a that connect the crank shaft and the power pneumatics 1 are similarly adapted to be snapped into and out of operative position exactly as above described in connection with the longer pitmen 9, the movable boards of the power pneumatics 10 being each provided with a round cross-sectioned metal part 11 adapted to be received into and retained by the U-shaped end of the pitman, said part 11 being in turn supported by legs 11^a, which latter are preferably flattened as best shown in Fig. 2 so as to be rigidly securable by the screws 12 to the movable board of the motor pneumatics.

Of course, modifications and changes may be made in the above preferred embodiment 20 of my invention which will still be within the scope and spirit of the foregoing disclosure and within the scope and spirit of the annexed claims, which as such are intended to be covered thereby.

25 What I claim is:

1. A pitman for connecting the crank shaft of a pneumatic motor with an elongated round cross-sectioned part on the related slide valve of said motor, said pitman 30 consisting of a strip of spring-metal provided with bent-up, substantially U-shaped ends whose sides extend transversely to the body portion of said strip, said U-shaped ends being adapted in size and shape to be 35 sprung over the crank shaft and said round

cross-sectioned part and to be retained in place thereon by the resilience of the sides of said U-shaped ends.

2. A pitman for connecting the crank shaft of a pneumatic motor with an elongated round cross-sectioned part on the related slide valve of said motor, said pitman 40 consisting of a strip of spring-metal provided with bent-up, substantially U-shaped ends, the latter adapted in size and shape 45 to be sprung over the crank shaft and said round cross-sectioned part and to be retained in place thereon by the resilience of the sides of said U-shaped ends, and sound-deadening material lining said U-shaped 50 ends.

3. A pitman for connecting the crank shaft of a pneumatic motor with an elongated round cross-sectioned part on the related slide valve of said motor, said pitman 55 consisting of a strip of spring-metal provided with bent-up, substantially U-shaped ends, the latter adapted in size and shape to be sprung over the crank shaft and said round cross-sectioned part and to be retained 60 in place thereon by the resilience of the sides of said U-shaped ends, sound-deadening material lining said U-shaped ends, and clamping lugs on said pitman adjacent the mouth of said U-shaped ends engaging said 65 lining material.

In testimony whereof I have signed my name to this specification this 15th day of May, 1926.

FRED VOLARE
